GUITAR CONSTRUCTION

Filed Sept. 10, 1930

FIG. IV.

INVENTOR.

B. J. PUOINA
BY *Victor J. Evans*
ATTORNEYS.

UNITED STATES PATENT OFFICE

BENJAMIN K. PUOKA, OF KAHULUI, TERRITORY OF HAWAII

GUITAR CONSTRUCTION

Application filed September 10, 1930. Serial No. 481,028.

This invention relates to improvements in guitars, of that type commonly known as steel guitars.

The principal object of the invention is 5 to produce a guitar which is simple in construction, and one which has a better tone quality.

Another object is to produce a guitar 10 wherein the resonance chamber is greatly increased in size.

Other objects and advantages will be apparent during the course of the following description.

In the accompanying drawings, forming a 15 part of this specification, and in which like numerals are employed to designate like parts throughout the same,

Figure I is a top plan view of my improved 20 guitar,

Figure II is a side elevation of Figure I,

Figure III is a view similar to Figure I with the top removed, and

Figure IV is an elevation of the pocket board.

25 Steel guitars are played with the guitar laying upon the lap or knees of the player and the strings are picked with one hand while the fretting is done with a steel piece held against the strings. In this type of guitar, it has been common to form the handle or neck of the guitar of a solid piece of wood secured to the resonance chamber or drum portion of the guitar. The result is that the guitar could only have a resonance chamber 30 equal to the size of the drum portion. By my improved method of construction, it is possible to increase the resonance chamber so as to take in the entire handle portion and to also include in the resonance chamber a sound pocket in a manner to be hereinafter described.

In the accompanying drawings, the numeral 5 designates the side of the guitar which is preferably formed of a thin wood 45 bent to proper shape, which shape may be any desired form to accomplish the purpose sought to be realized.

It will be noted that the ends 6 and 7 converge toward each other and are secured 50 to the head 8 which is preferably a solid

block in which the string tightening keys are located.

A top 9 and bottom 11 are secured to the side pieces of the guitar in any approved manner. The top 9 has sound openings 12 55 formed in the surface thereof and sound openings 13. These openings may be of any desired shape so as to permit sound to escape from the chamber 14.

A sound chamber 16 is formed in the drum portion by providing a chamber board 17 which extends from side to side of the guitar and from top to bottom thereof. A portion of the board is cut away as shown at 18 so as to permit the vibrations to pass from the 60 chamber 16 to the resonance chamber 14. The customary strings are provided as shown in Figure I.

In order to prevent splitting of the side board 5, I provide re-enforcing blocks 19 70 which blocks prevent the lengthwise cracking of the fine material from which the guitar is constructed, or if a crack starts, these blocks will stop the same from extending the entire length of the strip.

75 The result of this construction is that when the guitar is played, due to the fact that the handle portion of the guitar is hollow a much greater volume will be given out, which volume will also have better tone quality 80 than has been produced in steel guitars heretofore.

This tone quality is also mellowed by the creation of the chamber 16 which in some manner dampens the vibrations so as to produce a more mellow quality of music without increasing the volume.

85 It is to be understood that the form of my invention herewith shown and described is to be taken as a preferred example of the 90 same and that various changes relative to the shape, size, material and arrangement of parts may be resorted to without departing from the spirit of the invention or the scope of the subjoined claim.

95 Having thus described my invention, I claim:—

In a guitar, a side piece, top and bottom pieces secured to said side piece, a head secured to said side piece, said construction 100

forming a tone chamber extending substantially the entire length of the guitar and a partition board positioned in said tone chamber and spaced from one end thereof, said 5 partition board having a portion thereof cut away so as to form communication throughout the entire length of the guitar.

In testimony whereof I affix my signature.
BENJAMIN K. PUOINA.
